UNITED STATES PATENT OFFICE

161,363

POTTER'S WHEEL

Elena M. Netherby, Oakland, Calif.

Application July 25, 1949, Serial No. 4,124

Term of patent 14 years

(Cl. D33—14)

To all whom it may concern:

Be it known that I, Elena M. Netherby, a citizen of the United States, residing at Oakland, in the county of Alameda and State of California, have invented a new, original, and ornamental Design for a Potter's Wheel, of which the following is a specification, reference being had to the accompanying drawing, forming part thereof.

Fig. 1 is a side elevation,
Fig. 2 is a top plan view,
Fig. 3 is a rear elevation, and
Fig. 4 is a front elevation of a potter's wheel,
showing my new design.

I claim:

The ornamental design for a potter's wheel, as shown.

ELENA M. NETHERBY.
